UNITED STATES PATENT OFFICE.

GODFREY H. LASAR, OF ST. LOUIS, MISSOURI.

TYPE-WRITING MACHINE.

SPECIFICATION forming part of Letters Patent No. 415,528, dated November 19, 1889.

Application filed October 11, 1886. Renewed October 22, 1889. Serial No. 327,785. (No model.)

To all whom it may concern:

Be it known that I, GODFREY H. LASAR, of the city of St. Louis, in the State of Missouri, have invented a certain new and useful Improvement in Type-Writing Machines, of which the following is a full, clear, and exact description, reference being had to the accompanying drawings, forming part of this specification, and in which—

10 Figure 1 is a top view illustrating my improvement. Fig. 2 is a side elevation. Fig. 3 is a rear elevation. Fig. 4 is a detail front elevation. Fig. 5 is a horizontal section taken on line 5 5, Fig. 2, looking in the direction of the arrows. Fig. 6 is a detail section showing part of the carriage-roller and part of the ribbon-holder.

15 This invention relates to improvements in ribbon spools and holders for type-writers; and it consists in features of novelty herein-after fully described, and pointed out in the claims.

Referring to the drawings, A represents the paper-roller, and B represents a block supported on a stem B', by which it is secured to the main frame or base of the type-writer. Dovetailed into the block B is a laterally-moving frame C, which carries the ribbon-spools D and E, the block B being provided 25 with a set-screw B², by which the frame C may be shifted sidewise to change the position of the surface of the ribbon on which the type strikes, the inner end of the screw B² entering the part C of the frame that is dovetailed 30 into the block B. The frame C has projections C', into which are screwed inclined journal-pins F, as shown in Fig. 5. Upon the journal-pins F fit ratchet-wheels G, which have hubs G', provided with flanges G², and 35 extending outward from the hubs G' are non-circular extensions G³, over which slip the spools D and E, the sockets in the spools corresponding in shape with the extensions G³. The spools are held in place on the extensions 40 by spring-catches H, secured to the extensions G³ in slots or openings H'. It will thus be seen that by simply pressing inward on the springs H the spools may be removed, and it will also be seen that the spools will be made 45 to revolve or turn with the ratchet-wheels G. The ratchet-wheels are held upon the journals

5 F by means of a U-shaped frame I, the upper ends of which fit in the hubs G' between the flanges G². (See Fig. 4.)

While the frame prevents the ratchet-wheels from slipping off the journals, it does not interfere with their rotary movement. The frame I is pivoted to the frame C at I', and its tension against the hubs G' is increased or diminished by a set-screw I², and 60 by loosening the set-screw the frame may be moved back from the hubs G' to permit of the removal of the ratchet-wheels from the journal-pins.

In Fig. 2 the spool and ratchet-wheel on the 65 side of the device presented in the figure are removed.

J represents a bifurcated dog, the respective arms J' of which engage the respective ratchet-wheels G. The dog is pivoted to a lever L at 70 L' so as to be swung or moved into engagement with either of the ratchet-wheels, so that the ribbon M may be alternately wound from one onto the other, and the dog is held in engagement with the ratchet-wheel by a 75 spring J², connecting it to the frame C. The lever L is pivoted to the frame C at L², and may be provided with a finger-piece L³, by which it may be depressed to turn the spools through means of the dog; or it may be connected by a bar or rod L⁴ to a bar or rod (not shown,) extending beneath the key-levers of the machine, so that each time a key-lever is operated the spools will be turned. In another application, Serial No. 232,733, filed March 28, 80 1887, I have shown, described, and claimed an equivalent means for feeding the ribbon. The upper end of the frame C projects inwardly toward the roller, forming a horizontal portion C².

90 The ribbon M passes from one spool up and over a bar N, which is inclined toward the roller, forward and around the front end of an arm O, which projects over the roller, back and over a bar N', which is inclined 95 toward the roller, and down to the other spool, the bars N and N' having vertical projections N² and the arm O having projections O' extending horizontally rearward to prevent the displacement of the ribbon. 100 The arm O extends over the paper-roller A, as stated, and holds the ribbon in close

proximity to the roller, as shown in Fig. 2. To permit of the arm being thrown up, as shown in Fig. 6, to expose the roller and the printing it is hinged to the frame C, 5 which supports it, at O², and when thrown up it comes against a projection O³ on the frame C. It is held in its lower position, against a projection O⁴, by a spring O⁵, connecting a lug O⁶ on the arm to the frame C, as shown 10 in Fig. 2. With this arrangement the ribbon is supported in a line diagonal to the length of the roller A and is supported above the roller to permit of the printing being done on top of the roller, where it can be more conveniently 15 inspected than when done beneath the roller, such an arrangement being convenient to be used in connection with a machine where the type-bars have a downward movement—as, for instance, like that shown 20 in my application Serial No. 215,907. The ribbon is made to cross itself, as shown in Fig. 1, so that where it is desired to print through a single thickness of the ribbon, (instead of through a double thickness,) as 25 shown in my application Serial No. 315,145, it may be done.

I claim as my invention—

1. In a type-writer, the combination, with a frame extending upward and inward and 30 provided with ribbon-spools, of the bars N and N', secured to the frame and projecting laterally therefrom, the arm O, extending from the frame over the roller, and a ribbon extending from the spools over and under the 35 end of the arm obliquely to the length of the roller.

2. In a type-writer, the combination of the

frame, spools secured to the frame, arm for supporting the ribbon over the paper-roller, block supporting the spool-frame, and screw 40 for adjusting the spool-frame, substantially as and for the purpose set forth.

3. In a type-writer, the combination of a frame extending upward and inward and ribbon-spools, the spool-journals inclined to 45 toward the roller, guide-bars inclined toward the roller, arm extending inward from the frame over the roller, and a ribbon extending from spool to spool over and under the end of the arm obliquely to the length of the 50 roller.

4. In a type-writer, the combination of the frame, projections on the frame, journal-pins secured to the projections, ratchet-wheels having flanged hubs and extensions and fitting on the journal-pins, spools fitting on the extensions of the ratchet-wheels, spring-catches for holding the spools on the extensions, and frame fitting in the flanged hubs of the ratchet-wheels, substantially as and for 60 the purpose set forth.

5. In a type-writer, the combination of the frame, projections C' on the frame, journal-pins F, secured to the projections, ratchet-wheels G, flanged hubs G', secured to the 65 ratchet-wheels and having extensions G³, spools fitting on the extensions, springs H, hinged frame I, bearing against the hubs G' of the ratchet-wheels, and set-screw I², substantially as set forth.

GODFREY H. LASAR.
